(57) **CLAIM**

The ornamental design for a steering wheel for car, toy car replica, and/or other replicas, as shown and described.

DESCRIPTION

FIG. 1 is a front perspective view of the steering wheel for car, toy car replica and/or other replicas showing my design; FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom view thereof.

Portions of the steering wheel shown in broken lines form no part of the claimed design.
